UNITED STATES PATENT OFFICE.

JOSEPH KLEPAC, OF NEW YORK, N. Y., ASSIGNOR TO BRAMBACH PIANO COMPANY, A CORPORATION OF NEW YORK.

PIANISSIMO DEVICE FOR GRAND PIANOS.

Application filed June 16, 1921. Serial No. 478,202.

To all whom it may concern:

Be it known that I, JOSEPH KLEPAC, a citizen of the United States residing at New York, in the county of New York and 5 State of New York, have invented a new and useful Pianissimo Device for Grand Pianos, of which the following is a specification.

The object of this invention is to improve 10 the pianissimo or soft pedal device of a piano action, particularly a grand piano action. The common way of obtaining a pianissimo effect in grand pianos is to shift the entire action sideways or laterally so that when such adjustment is made 15 the hammers will strike only a part of the wires or strings making up each note. This is not altogether a satisfactory device, because only one wire or string is used for 20 the upper notes, because overtones come from the strings or wires that are not struck, because many of the parts are apt to rattle owing to the loose arrangement necessary, and because the shifting causes the hammers 25 to strike in different positions laterally wearing the hammer felts unevenly.

To overcome these defects, I have provided 30 a pianissimo device which greatly improves the grand piano action. This improved device is arranged as follows: The hammers are pivoted rigidly to the hammer rail and the hammer rail is rigidly mounted in action brackets which are rigidly secured in position. Thus, each hammer 35 swings from a fixed pivot whether the soft pedal is used or not. The wippen rail on which the wippens of the actions are pivoted is mounted so that it can move substantially vertically. The hammer rest rail is 40 also mounted so that it can move vertically. Connections are provided between these two rails so that the wippen rail and the hammer rest rail will move oppositely, the hammer rest rail having a slightly greater movement 45 than the wippen rail. Although not necessary, the regulating rail which carries the regulating screws, which operate the jacks, is also arranged to move with the wippen rail and the hammer rest rail so that when 50 these latter are moved the exact relations between the parts of the action will be preserved.

One convenient way to arrange these parts is to carry the wippen rail on the 55 ends of levers or arms pivoted to the rigid

action brackets, to carry the hammer rest rail on the ends of levers or arms pivoted to a stationary part and to connect these levers together by suitable links. The levers which carry the wippen rail can be 60 extended beyond their pivots and the rest rail can be carried by these extensions. The soft or pianissimo pedal is connected to this system of levers. Springs are preferably arranged so that the wippen rail is 65 normally raised to upper position, the connections before described being arranged so that when the wippen rail is in normal position the hammer rest rail and the regulating rail will also be in normal position. 70 When the soft pedal is depressed, the connections therefrom are so arranged that the wippen rail will be depressed, the hammer rest rail will be raised and the regulating rail will be moved upwardly. As 75 this action takes place the wippens will pivot on the capstan screws on the keys and this pivoting will partially operate the actions so as to raise the hammers the proper degree. By this arrangement, when 80 the soft pedal is operated the hammers will occupy a position nearer the strings so that the travel of the same will be shortened and hence the pianissimo effect will be obtained.

My improved device has the great advantages that the hammers always swing from fixed pivots so that they will always strike the strings in the same relation. There is no sideways shifting of the hammers. The manual operation of the keys or 85 the depressing of the front ends of the keys is the same no matter whether the actions are operated with the parts in normal relation or whether they are operated while adjusted for pianissimo playing. 90 Thus, the touch or feel of the piano is precisely the same no matter whether the soft pedal is or is not depressed. When the actions are adjusted for pianissimo playing the repetition parts of the actions still remain in exact relation for repetition playing. There is no lost motion between the keys and the actions as when adjustments for soft playing are made, the wippens pivot 95 around the capstan screws on the keys. In 100 brief, the operation of the pianissimo device does not in any way affect the feeling or leverage of the keys. It also will be noted that the action brackets are rigidly secured in position and as the hammer rail 105

is rigidly secured thereto there is very little chance for the parts to rattle or get out of adjustment.

By these improvements I have greatly improved the operation of grand pianos.

The invention is illustrated in the accompanying three sheets of drawings, referring to which and in detail—

Fig. 1 is a cross sectional elevation 10 through the action illustrating the parts in position for normal playing;

Fig. 2 is a view just inside one of the action supporting brackets showing the connections whereby the wippen rail is adjusted 15 or set from the soft pedal;

Fig. 3 is a sectional elevation on an enlarged scale showing the way the wippen rail and the hammer rest rail are mounted and connected, the dotted lines showing the 20 opposite adjustment of the rails to position for pianissimo playing;

Fig. 4 is a sectional elevation through the action illustrating the normal position of the action in full lines and the position for 25 pianissimo playing in dotted lines, and

Fig. 5 is a perspective view of the connections which may be employed for adjusting the parts by the operation of the soft or pianissimo pedal.

Referring to the drawings and in detail, 30 1 designates a white key, 2 a black key, which keys have the usual leads 3. 4 designates the key frame having the front rail 5, balance rail 6 and the back rail 7. The front 35 rail 5 is provided with pins 8 which guide the front ends of the keys and also with punchings or pieces of felt 9 on which the keys strike. The balance rail 6 is provided with pins 10 on which the keys pivot and 40 with punchings or pieces of felt arranged on the pins so as to come between the keys and the balance rail. The back rail 7 is provided with pieces of felt 12 on which the back ends of the keys normally rest. Each 45 key is provided with a curved head capstan screw 13, which engages with a curved felted or cushioned section 140 of a wippen 14 of the action. Each wippen 14 is pivoted to a flange or block 15 secured to the wippen rail 16. A jack 17 is pivotally mounted on the 50 front end of each wippen and has a heel 18. A repetition lever 19 is pivoted to a flange or block 20 carried by each wippen. A wire spring 21 is pivoted on each repetition lever 55 19 and the tension of the same can be adjusted by a regulating screw 22. The rear end of each spring 21 on each repetition lever 19 is connected by a silk cord 23 to the rear end of its wippen. Each repetition lever 19 is provided with a screw 24 which strikes on its wippen, whereby the normal 60 position of the repetition lever can be adjusted. A spoon 25 is secured to the front of each repetition lever in position to strike 65 on a screw 26 having a felted head. The

hammer butts 27 are pivoted to flanges or brackets 28 rigidly secured to the hammer rail 29 which latter is rigidly secured to the action supporting brackets hereafter referred to. Each hammer butt 27 is provided with a felted extension which is engaged by a jack 17. The hammer shanks 30 extend from the butts and each shank carries a hammer head and felt 31 at its rear end, to strike on the string or strings 32. 33 designates the hammer rest rail which comes close to the hammer shanks and against which the hammers fall and rebound as they recede from the strings. 34 designates the back checks which are carried by the rear ends of the keys. A felt 35 is mounted on the rear of each key to engage a damper lever 36 pivoted on a bracket 37 secured to the damper action rail 38. A butt 39 is pivoted to each damper lever 36 and a wire 40 extends from the same through a guide bracket 41 and carries a damper head 42 having pieces of felt 43—43 which engage with the strings. The damper levers 36 can be leaded or weighted as at 44. The damper levers 36 are provided with regulating screws 45 having felted ends 46 to engage on a stop device 450. The damper arrangements are carried by the head piece 47 of the piano. The jacks 17 carry regulating screws 48 having felts 49 for engaging spoons 50 secured to the wippens 14. Springs 51 are arranged between the lower ends of the jacks and abutments extending down from the wippens.

The action is carried in action supporting brackets 52 which are rigidly secured in place. A regulating screw 53 having a felted end 54 is provided for each jack heel 18, these screws being tapped into a regulating rail 55. The above parts constitute an action of a well known or approved form.

To get the results previously mentioned, the wippen rail 16 and the hammer rest rail 33 are made floating or movable and are connected to move oppositely as hereinafter described. The wippen rail 16 is mounted or carried on the ends of levers 60—60, which are hung on pivots 61—61 on the inside faces of the rigid action brackets 52. 115 The regulating rail 55 is carried by the outer ends of these levers 60—60. The hammer rest rail 33 is carried by levers 62—62 pivoted to the end hammer flange or bracket or to special brackets 28—28 secured to the hammer rail. The levers 60—60 are connected to the levers 62—62 by links 63. By the connections thus described it will be seen that as the wippen rail 16 moves downwardly, the hammer rest rail will move upwardly and vice versa.

Each action bracket 52 is made to form a yoke 64, which yokes form slots in which the wippen rail 16 moves up and down. A spring 65 is arranged in a pocket in each 130

action bracket 52 to bear on the under side of the wippen rail 16 near its ends, so as to force the same normally upward. A screw 66 having a large head 67 is threaded into 5 the upper part of each yoke 64 to limit the upward movement of the wippen rail. Screws 68 having large heads 69 are threaded into the wippen rail at each end thereof and these screws are set to bear on 10 pieces of felt 70 secured to the action bracket 52, these screws thus serving to limit the downward movement of the wippen rail. The wippen rail is thus normally held in its upper position.

15 When the pianissimo effect is desired, the mechanism which depresses the wippen rail is operated and the wippen rail is forced downwardly against the tension of the springs 65. The mechanism for forcing the 20 wippen rail downwardly is shown in detail in Figs. 2 and 5. A lever 71 is set in position to be engaged by the rod 72, extending upwardly from the soft pedal, which pedal rod is raised when the soft or pianissimo 25 pedal is depressed. This lever 71 is pivoted to a bracket 73 secured to the key frame 4. The lever 71 connects at its rear end by a link 74 to a lever 75 mounted on a shaft 76 journaled in brackets 77—77 secured to the 30 key frame. Spring arms 78 are secured to the wippen rail 16 and these arms are engaged by spring arms 79—79 extending from the shaft 76. If desired, pieces of felt 80 may be arranged between these arms. Any 35 other suitable connections may be arranged between the soft or pianissimo pedal and the wippen rail.

When the soft pedal is not depressed the parts are in normal position, as shown in 40 full lines in the drawings, and the action is in ordinary or normal position.

Now, when the soft pedal is depressed the wippen rail 16 is forced downwardly. As the wippen rail is moved downwardly the 45 extensions 140 of the wippens will bear on the capstan screws 13 of the keys and as the rear ends of the wippens move downwardly with the wippen rail, the front ends of the wippens will move upwardly. This will set 50 the action to the position shown in dotted lines and will raise the hammers nearer to the strings. As the wippen rail is moved downwardly the hammer rest rail will be moved upwardly to follow the hammers so 55 that this rail will stand in proper relation with the hammers when they are adjusted for their shortened stroke. The regulating rail 55 also will move upwardly with the jacks carried at the front ends of the wippens so that the proper relation between the 60 parts of the action will be preserved when adjustment is made. It will be seen that this adjustment does not depress the keys.

Now, when the keys are struck, the pianissimo effect will be obtained and by reason 65

of the curved engagement between the abutments 140 and the screws 13 the leverage and manipulation of the keys will be just the same as for normal playing. It will be noted that the hammers always swing on 70 rigid or fixed pivots as the hammer rail 29 is rigidly secured to the two action brackets 52 which are rigidly secured in position. By this arrangement the hammers will always strike the strings in the same lateral 75 position, the pianissimo effect being obtained by shortening the hammer stroke. It also will be noted that when the wippen rail and connected parts are adjusted for pianissimo playing, the adjustment of the action 80 does not effect or disturb the parts that are provided for repetition playing. Hence, the exact touch of the piano is preserved, no matter whether it is being played normally or to obtain the pianissimo effect. Thus, the 85 operation is greatly improved.

It also will be seen that the rails may be adjusted to any intermediate position between that shown in full lines and the dotted lines so that any degree of the pianissimo 90 effect between these two extremes can be obtained.

If the piano is also to be played mechanically, the rear ends of the keys may be engaged by abstracts 82 arranged in the 95 usual manner.

The details and arrangements herein shown and described may be greatly varied by a skilled mechanic without departing from the scope of my invention as expressed 100 in the claims.

Having thus described my invention what I claim and desire to secure by Letters Patent is:—

1. In a piano action, the combination of a 105 fixed piano rail, hammers pivoted thereto, a movably mounted wippen rail, wippens pivoted thereto, operating connections between the wippens and hammers, curved abutments on the wippens, keys having means engaging the curved faces of said abutments, and means for moving the wippen rail to adjust the stroke of the hammers, the wippens engaging said means so that the leverage and stroke of the keys will not be changed by 110 the adjustments of the wippen rail.

2. In a piano action, the combination of a 115 fixed hammer rail, hammers pivoted thereto, a movably mounted wippen rail, wippens pivoted thereto, operating connections between the wippens and hammers, curved felted abutments on the wippens, keys having curved headed screws engaging the curved faces of said abutments, and means for moving the wippen rail to adjust the 120 stroke of the hammers, the wippens engaging said screws so that the leverage and stroke of the keys will not be changed by 125 the adjustments of the wippen rail.

3. In a piano action, the combination of a 130

movable wippen rail to which the wippens are pivoted, a movable hammer rest rail, connections between the rails so that they will move oppositely, and means for adjusting these rails to adjust the hammer stroke.

4. In a piano action, the combination of a movable wippen rail carrying the wippens, a movable regulating rail, connections to which the rails are attached so that the relation between the same will be preserved, and means for adjusting these rails to adjust the hammer stroke.

5. In a piano action, the combination of a movable wippen rail carrying the wippens, 15 a movable hammer rest rail, a movable regulating rail, connections between the wippen rail and the hammer rest rail, so that the wippen rail will move oppositely to the movement of the regulating rail and hammer rest rail, and means for moving the rails to adjust the hammer stroke.

6. In a piano action, the combination of fixed action brackets, a hammer rail, to which the hammers are pivoted, secured to 25 said brackets, levers pivoted to said brackets, a wippen rail carrying the wippens carried by the rear ends of said levers, and means for adjusting the wippen rail to vary the hammer stroke.

30 7. In a piano action, the combination of fixed action brackets, a hammer rail to which the hammers are pivoted, secured thereto, levers pivoted to said fixed action brackets and carrying at their rear ends a wippen rail to which the wippens are pivoted, pivoted levers carrying the hammer rest rail, links connected between said two sets of levers so that the wippen rail and hammer rest rail will move oppositely, and 35 means for adjusting the rails to adjust the hammer stroke.

45 8. In a piano action, the combination of fixed action brackets, levers pivoted thereto and carrying at their rear ends a wippen rail to which the wippens are pivoted, a regulating rail secured to the front ends of said levers, levers hung on pivots supported by the fixed action brackets, a hammer rest rail carried thereby, links extending from 50 the front ends of the first named levers to the second named levers, and means for adjusting the rails to vary the hammer stroke.

9. In a piano action, the combination of fixed action brackets, a hammer rail secured thereto to which the hammers are pivoted, 55 levers pivoted to said brackets and carrying at their rear ends a wippen rail to which the wippens are pivoted, a regulating rail carried by the front ends of said levers, levers pivoted to the fixed hammer rail and 60 carrying the hammer rest rail at their rear ends, connections extending from the front ends of the first named levers to the second named levers, and means for adjusting the rails to vary the hammer stroke.

65 10. In a piano action, the combination of fixed action brackets, a hammer rail rigidly secured thereto to which the hammers are pivoted, a wippen rail movably connected to said brackets and carrying the wippens, 70 springs in the fixed action brackets normally forcing the wippen rail upwardly, and means for moving the wippen rail downwardly and adjusting the hammers on their fixed pivots to vary the hammer stroke.

75 11. In a piano action, the combination of fixed action brackets, a hammer rail secured thereto to which the hammers are pivoted, a movable wippen rail carrying the wippens, 80 springs for normally forcing the wippen rail upwardly, screws in the action brackets for limiting the motion of the wippen rail, and means for depressing the wippen rail to adjust the hammers upwardly on their fixed pivots to vary the hammer stroke.

85 12. In a piano action, the combination of fixed action brackets, a hammer rail secured thereto to which the hammers are pivoted, levers pivoted to the fixed action brackets, a wippen rail carried by the rear ends of the 90 levers to which the wippens are pivoted, springs in the fixed action brackets for normally forcing the wippen rail upwardly, levers pivoted to the hammer rail carrying the hammer rest rail at their rear ends, connections between the two sets of levers so that the wippen rail and hammer rest rail 95 will move oppositely, and means for moving the wippen rail downwardly to vary the hammer stroke.

100 In testimony whereof I have hereunto affixed my signature.

JOSEPH KLEPAC.
